UNITED STATES PATENT OFFICE.

WILLIAM H. DEWAR, OF PHILADELPHIA, PENNSYLVANIA, ASSIGNOR TO THE POOLEY COMPANY, OF PHILADELPHIA, PENNSYLVANIA, A CORPORATION OF PENNSYLVANIA.

DESIGN FOR A RADIO PHONOGRAPH CABINET.

Application filed June 30, 1925. Serial No. 13,954. Term of patent 7 years.

To all whom it may concern:

Be it known that I, WILLIAM H. DEWAR, a citizen of the United States, residing in Philadelphia, county of Philadelphia, State of Pennsylvania, have invented a new, original, and ornamental Design for Radio Phonograph Cabinet, of which the following is a specification, reference being had to the accompanying drawing, which forms a part thereof.

The figure is a perspective view of a radio-phonograph cabinet, embodying my design.

I claim—

The ornamental design for a radio phonograph cabinet, as shown.

WILLIAM H. DEWAR.
